UNITED STATES PATENT OFFICE.

ALPHONSE SIMPIER, OF ALBUQUERQUE, NEW MEXICO.

NAIL-DRIVER.

1,052,978.

Specification of Letters Patent. Patented Feb. 11, 1913.

Application filed April 9, 1912. Serial No. 689,634.

To all whom it may concern:

Be it known that I, ALPHONSE SIMPIER, citizen of the United States, residing at Albuquerque, in the county of Bernalillo 5 and State of New Mexico, have invented new and useful Improvements in Nail-Drivers, of which the following is a specification.

My present invention pertains to means for holding and driving nails and the like; 10 and it has for its general object to provide a simple, compact and durable device designed more especially for facilitating the nailing of soles on shoes and constructed with a view to containing a number of nails 15 in a magazine, supplying the nails one by one in proper fashion and in proper position to a holder, and displacing the nails one by one from said holder and driving the nails.

20 The invention in all of its details will be fully understood from the following description and claim when the same are read in connection with the drawings, accompanying and forming part of this specification, in which:

Figure 1 is an elevation of my novel device. Fig. 2 is a view, partly in diametrical section and partly in elevation, of the same. Fig. 3 is a view, partly in section and partly 30 in elevation, taken at a right angle to Fig. 2. Figs. 4 and 5 are detailed views hereinafter specifically referred to.

Similar numerals of reference designate corresponding parts in all of the views of 35 the drawings.

Among other elements my novel device comprises a cylindrical casing section 1, that is reduced and exteriorly threaded at its opposite ends for the connection of an apertured cap 2 and a lower casing member 3; the exterior of the said cap 2 and the exterior of the said member 3 being preferably 40 roughened as shown in Fig. 1, to render easy turning of the same on and off the section 1.

Mounted and adapted to rotate at one side of the member 3 and extending below the same is a toothed wheel 4. The teeth of the said wheel 4 are arranged at a distance 45 apart corresponding to the distance at which the nails are to be placed apart, and when the operator in pushing the device with his hand in which the same is held feels one of

the teeth of the wheel 4 engage the leather, the operator is apprised of the fact that he 55 has moved the device far enough to properly position the nails apart.

Connected by a conventional screw 5, a thumb-screw or any other suitable means to the lower end of the member 3 is a gage 6. 60 The said gage 6 is longitudinally slotted for the passage of the shank of the screw 5, and is designed to enable the operator of the device to position the nails at a distance desired from the outer edge of the sole that is 65 to be nailed to a shoe vamp.

Suitably fixed with respect to the casing section 1 is a magazine 7 designed to contain the nails to be driven. The said magazine has a bottom wall 8 which is pitched or inclined downward toward the said casing section 1, and is provided, in turn, with a slot 9 designed to receive the nails after the manner shown in Fig. 3, and support the nails by the heads thereof; the said heads being 75 larger than the slot 9 is wide. In communication with the slot 9 in the bottom of magazine 7 is a vertical slot 10 in the wall of the cylinder section 1.

Fixed by a screw 11 or other suitable 80 means in the cylinder section 1 is a metallic core 12, Figs. 2, 3 and 4. The said core is provided with a vertical central bore 13, and guided in the said bore and in the central aperture of the cap 2 is the reciprocatory 85 nail-driving plunger 14. Said plunger is of metal, and is preferably, though not necessarily, provided with a head 15, of leather or analogous material, designed to receive the blows of a hammer or mallet. At an intermediate point of its length the plunger 14 is provided with an enlargement 16, designed to bring up against the cap 2 and limit the upward movement of the plunger, and immediately below the said enlargement 90 16 the plunger is provided with a lateral upwardly tapered portion 17, best shown in Figs. 2 and 3. At a slight distance below the tapered portion 17 the plunger has an abutment 18, and between the said abutment 100 and the bottom of a socket 19 in the core 12 is interposed a coiled spring 20, having for its function to return the plunger to and yieldingly retain the same in the normal position shown in Figs. 2 to 4.

Opposed to each other and arranged in

the vertical center of the casing member 3 are nail-receiving and holding jaws 21. The said jaws are provided in their outer sides with shallow sockets 22, which sockets are disposed above and below the horizontal center of the jaws, and are designed to receive coiled springs 23 which are arranged between the jaws and the wall of the member 3, and have their outer ends maintained in position by screws 24, bearing in the member 3. By virtue of said construction it will be manifest that the jaws are adapted to receive a nail that gravitates to a position within them, and are also adapted to hold the said nail in the vertical center of the device and hence in vertical alinement with the plunger 14. It will further be manifest that when the plunger is impelled downward, the jaws will give outwardly and will consequently enable the plunger to properly drive a nail home into and through a shoe sole or other article that is to be nailed to another article.

Formed in the core 12 is a nail passage 25 the lower end of which is disposed above and adapted to discharge nails into the space between the jaws. At its upper end the said passage 25 merges into a vertical passage 26 formed in the side of the core 30 and having its upper portion increased in width and arranged opposite the slot 10 in the casing section 1, as shown by dotted lines in Fig. 5.

Suitably guided in the casing section 1 and the core 12 is a rectilinearly and horizontally movable separator 27 which is so denominated because it has for its function to assure the nails passing one by one from the bottom of the magazine and through the slot 10 and the passages 26 and 25. The said separator 27 is returned to and yieldingly retained in the position shown by a spring plate 28, fixedly connected at one end to the outside of the casing section 1, 45 and bearing at its opposite end against one end of the separator. It will also be observed that the separator is provided with a lateral arm 29 that is opposed to the tapered portion 17 of the plunger 14, and 50 that the separator is further provided with a nail passage 30; the latter being preferably of the shape shown in Fig. 4, and being normally held out of registration with the coincident slots in the casing section 1 and the magazine.

In the practical operation of my novel device, the operator grasps the cylinder section 1 in his left hand and moves the device step by step over the article that is to be nailed. When the device is properly positioned, the operator strikes the head 15 of the plunger 14 a sharp blow with a mallet, and consequently impels the plunger downward against the action of the spring 65 20. Such downward movement of the plun-

ger will be attended by driving the nail previously positioned between the jaws 21, and will also be attended by movement of the separator 27 under the action of the spring 28 so as to put the passage 30 into registration with the slot 10 and enable the lowermost pendent nail of the series in the slot 9 to enter the outer portion of the passage 30. Subsequent to the described downward movement of the plunger 14, the said plunger will be moved upward by expansion of the spring 20, and incidental to such upward movement, the tapered portion 17 acts against the separator arm 29 and moves the separator 27 in the direction indicated by arrow in Fig. 4, and against the action of the spring 28, with the result that the nail received in the passage 30 of the separator is separated from the other nails and is dropped into the upper wide portion of the passage 26 from whence it passes through the passage 25 and assumes its proper central and upright position within and between the jaws 21, ready to be driven on the succeeding downward movement of the plunger 14.

It will be gathered from the foregoing that in the operation of my novel device the proper feed of the nails is assured by the shock and jar incidental to each blow imposed on the head of the plunger 14; and it will also be appreciated that the device as a whole is simple, compact and strong in construction, and hence is well adapted to withstand the rough usage to which devices of corresponding character are ordinarily subjected.

Having described my invention, what I claim and desire to secure by Letters-Patent, is:

In a nail holding and driving device, the combination of a casing having a vertical slot in the upper portion of the same, a magazine fixed at one side of the casing and having an inclined bottom and a slot in said bottom communicating with the vertical slot in the casing, a body arranged in the casing and having a nail passage in its side, a plunger guided in the said body and having a lateral upwardly-tapered portion movable in the body, a spring constructed and arranged to raise the plunger to and yieldingly maintain the same in its normal position, a rectilinearly and horizontally movable nail-separator guided in the casing and body and between the latter and the magazine and having a lateral arm at one side of the body opposed to the said tapered portion of the plunger and also having an end portion extending beyond the opposite side of the body and the casing and further having a nail-receiving passage adapted on downward movement of the plunger to be registered with the slots in the casing and magazine bottom and also adapted on the

upward movement of the plunger to be moved out of said registration, and a spring strip fixed at one end to the casing and connected at its opposite end to the said extended end portion of the nail-separator and tending to move said end portion of the nail separator inward.

In testimony whereof I have hereunto set my hand in presence of two subscribing witnesses.

ALPHONSE SIMPIER.
